UNITED STATES PATENT OFFICE.

CHARLES W. SCHLEIER, OF WELLSTON, MISSOURI.

FOLDING LUNCH-BOX.

1,018,378.

Specification of Letters Patent. Patented Feb. 20, 1912.

Application filed March 21, 1911. Serial No. 615,917.

To all whom it may concern:

Be it known that I, CHARLES W. SCHLEIER, a citizen of the United States, residing at Wellston, in the county of St. Louis and State of Missouri, have invented new and useful Improvements in Folding Lunch-Boxes, of which the following is a specification.

This invention relates to improvements in 10 that type of lunch boxes known as folding or "knock down," and one of the objects of the invention is to construct a box of this character which shall be simple, which can be manufactured at a low cost, and which 15 may be readily folded to provide a small package that may be carried in the pocket of the owner without unduly bulging the pocket or inconveniencing the owner.

Another object of the invention is the provision with a box of this character having 20 hinged sides and ends, of a lid or closure provided with a bail or handle and having means coöperating with the box for effectively securing the said closure to the box, 25 and for locking the hinged sections in their position.

Another object of the invention is to provide a folding lunch box having hinged sides and ends, the said sides and ends adapted 30 to interlock when the box is in a set-up position, and the side hinge extensions being provided with means whereby the said sides are effectively connected together when the sides are folded over the ends when the 35 box is in its knock down or folded position.

A still further object of my invention is the provision in a box of this character of a base having hinged sides and ends, each of the said sides and ends having its connecting pintle constructed of a spring element, the said springs adapted to automatically swing the sections to an open position after the locking device which retains the sections in their folded position has been 45 actuated.

With the above objects in view, and others which will appear as the nature of the invention progresses, the invention resides in the novel construction and arrangement of 50 parts hereinafter fully described and claimed.

In the drawings, accompanying this specification, there has been illustrated a simple and preferred embodiment of the improvement, it being understood, however, that the 55 showing therein is merely illustrative, and

that changes in the minor details of construction, as to shape, size, proportion, material, etc., which fall within the scope of the appended claim, may be made if desired.

In the drawings—Figure 1 is a perspective view of a box constructed in accordance with the present invention, the same being shown in its set-up position. Fig. 2 is a central longitudinal sectional view of the 60 showing. Fig. 3 is a transverse sectional view of the same. Fig. 4 is a similar section showing the box in its folded position. Fig. 5 is a detail perspective view of the upper portion of one of the hinged ends.

In the accompanying drawings, the numeral 1 designates my improved box, and 2 the lid or closure for the same. The box 1 comprises essentially a base 3, the same being preferably of a rectangular formation and having all of its edges upturned to 70 provide a substantially continuous flange 4. The upper edge of the flange is formed with a plurality of spaced extensions, the same adapted to be bent downwardly over the inner faces of the flange to provide the 75 "butts" 5, which are adapted to coact with upturned portions formed upon the lower edges of the side members 6 and 7 and the end members 8 and 9 which form the 80 extensions for the box. The upper edges of 85 the sides and ends are also bent downwardly upon their inner faces to provide the beads 10. Each of the sides and ends have their butts connected through the medium of a suitable pintle, and each of the said pintles 90 comprises the lower horizontal portions of spring members 11. By reference to Figs. 2 and 3 of the drawings it will be noted that each of the said springs is constructed of a single strand of resilient wire. The upper 95 portion of each of the wire springs is arranged longitudinally of the sides and ends, and the said upper portion is adapted to be positioned between the beads 10 and the sides and ends, and to be securely engaged 100 by the said beads. The upper portion of each of the springs is preferably arranged centrally of the sides and ends of the box, and the strands connected with the said top portion are brought downwardly at an angle 105 toward each other to provide what may be termed the legs 12 of the springs. The legs 12 of the springs are adapted to lie snugly against the inner faces of the sides and ends, and the portions of the spring forming the 110

pintle for the butts extend in opposite directions through the said butts and have their extremities bent or turned downwardly to provide the fingers 13 which normally contact with the inner faces of the flange of the base, and at corners thereof.

The opposite edges of the side members are flanged inwardly as designated by the numerals 14, and each of these flanges is provided with an opening 15. The end sections 8 and 9 are each provided, adjacent their edges with projections or pintles 16, and these projections are adapted to engage within the openings provided by the flanges of the sides when the box is in its set up position. By this arrangement, it will be noted that the sides and ends of the box are effectively sustained against outward movement when the said sides and ends are set up.

The end members 8 and 9 have their upper edges, preferably, centrally formed with inturned portions 17, the said inturned portions having their extremities bent upwardly to provide tongues 18. These tongues 18 are each formed with an orifice 19, the purpose of which will presently be set forth.

The closure 2 is of a size adapted to fit snugly over the hinged sides and ends, when the box is in its set up position and over the flange 4 of the base when the said sides and ends are folded upon the base. The closure 2 is formed with a continuous downturned flange 20, and the said flange is preferably constructed of some flexible material so that the said flange will frictionally engage with the base 3 to prevent the separation of the closure from the box when the latter is folded. The top 2 is provided with oppositely disposed slits or openings 21 and 22, the latter adapted to register with the tongues 18 of the end members 8 and 9.

The numerals 23 and 24 designate sliding bolt members which are mounted in suitable bearings 25 and 26 upon the top of the closure. These bolt members are preferably constructed of a single strand of suitable wire, having their inner portions off-set to provide a handle, and the said handle when abutting against either of the bearings 25 or 26 limits the sliding movement of the bolt in one direction. The closure is provided with suitable stop members 27 and 28, which are arranged within the path of the handles of the bolts and which are adapted to limit the movements of the said bolts in this direction. The bolts are adapted to engage with the orifices 19 or the flanges 20, and thus securely lock the closure upon the hinged sides and ends when the box is in its center position. The closure 2 is provided with a bail or handle 29, the latter also, preferably, constructed of a single strand of wire having its opposite ends downturned and passing through suitable openings provided by the said closure. The

extremities of the said downturned portions are off-set at opposite angles, so that the handle may be swung upwardly in only one direction. The off-sets of the handle are so arranged as to permit the handle to be swung closely against the top of the closure when the handle is not in use.

By reference to Figs. 2 and 4 of the drawings, it will be noted that one of the side members 7 is provided with a stud 30, while the opposite side member is indented as at 31 to provide a pocket which is adapted to receive the said stud and to secure the side 6 upon the side 7 after the end members 8 and 9 have been folded within the base 3.

From the above description, taken in connection with the accompanying drawings, the simplicity of the device, as well as the convenience thereof, will, it is thought, commend themselves to those skilled in the art to which such inventions appertain, and a further detailed description of the invention is deemed unnecessary except to state that the ends 8 and 9 are first folded within the flanged closure when the box is to be collapsed and that the sides are then folded one over another so that the stud 30 of one of the said sides engages the indented portion 31 of the second slide, thus securely locking the box in closed position, after which the closure 2 is placed over the collapsed box and its flanges frictionally engaging the flanges of the base retain the said closure upon the box. It will be also noted that the action of the spring members 11 is to swing the sections of the sides and ends to their open position, and it will be noted that the sides, which are provided with the inturned flanges are the first members to be opened, and that the springs acting upon the end sections will force the latter against the said flange, thus automatically setting up the box, while the interlocking of the sides and ends as well as the bolt members of the closure engaging within the orifices of the tongues of the ends render the box extremely strong and obviates either an inward or outward movement of the sides or ends.

It will be understood that the spring members may be dispensed with if desired, and that the cover provided with its locking elements will rigidly and effectively sustain the hinged sides and ends. It will be noted from the showing in the drawing that the said spring members are arranged upon the inner faces of the sides and ends as well as that they have their offset ends contacting with the inner faces of the flanged closure and that the said springs automatically self-adjust the sides and ends into their set up position, the flanges upon the sides serving as abutments for the ends, and as the said sides are the first to spring open, the projections upon the said sides will be

forced within the openings of the flanges, thus sustaining the box in a position to receive its contents and its locking cover.

Haying thus described the invention, what 5 is claimed is:

In a box for the purpose set forth, comprising a flanged base, the edges of the said base having integrally formed spaced butts, side and end members for the box, 10 each of said side and end members having one of their longitudinal edges formed with spaced butts adapted to be arranged between the butts of the flange of the base, the opposite longitudinal edges of the said sides 15 and ends being formed with inturned beads, a spring member having its upper portion arranged within the beads of each of the

sides and ends, said spring member providing spaced legs contacting with the inner faces of the sides and ends, the said legs being bent and extended through the butts in opposite directions, the extremities of the said members being bent downwardly contacting the flange of the base at the corners thereof, a flanged closure for the box, and 20 means for retaining the sides and ends upon the base when the said sides and ends are swung closed.

In testimony whereof I affix my signature in presence of two witnesses.

CHARLES W. SCHLEIER.
